ATTORNEY

UNITED STATES PATENT OFFICE.

JAMES W. BONTA, OF PHILADELPHIA, PENNSYLVANIA, ASSIGNOR TO THE AMERICAN NATIONAL TELEPHONE COMPANY, OF NEW YORK.

TELEPHONE-TRANSMITTER.

SPECIFICATION forming part of Letters Patent No. 365,776, dated July 5, 1887.

Application filed October 21, 1886. Serial No. 216,793. (No model.)

To all whom it may concern:

Be it known that I, JAMES W. BONTA, a citizen of the United States, residing at Philadelphia, in the county of Philadelphia and State of Pennsylvania, have invented certain new and useful Improvements in Telephonic Transmitters, of which the following is a specification, reference being had therein to the accompanying drawings, wherein—

10 Figures 1 and 2 are vertical sections showing my improvements.

My invention has relation to the form of telephonic transmitters shown and described in Letters Patent of the United States No. 15 333,816, and dated January 5, 1886, or that wherein a loose or rolling electrode is supported upon an inclined block or plate; and it has for its object simplicity of construction and arrangement of parts to produce an inexpensive, compact, and durable form of transmitter, as well as to intensify the impulses sent into the line for obtaining better working effects.

25 My invention accordingly consists of the combination, construction, and arrangement of parts, as hereinafter described and claimed, having reference particularly to locating the carbon block or inclined plate and loose or rolling electrode within the bore of the primary coil of the inductorium to make the transmitter more compact, and to increasing the diameter of the coils of the secondary of the inductorium and separating it more or less from the primary coil, which construction has 30 the effect of producing in the secondary more intense impulses for transmission to the line, and consequently more distinct articulation at the receiving end of the line.

In the drawings, A represents a suitable 40 form of transmitter box or easing having a hinged front or removable door or cap, a, provided with a mouth-piece, a', and diaphragm B, with or without electrode b.

C represents the secondary coil of the inductorium I, and E the primary coil of same. 45 The former is of a diameter relatively larger than that of the latter, so that the primary coil can be placed at an angle or inclined within the bore of the spool e for the second- 50 ary, as shown.

In the bore of the spool e, for the primary, is inserted a block of carbon or metal, F, of a semi-tubular form, upon which is the rolling or loose electrode G, for contact with the diaphragm-electrode b, the electrode G being shown as a ball. 55

The core or bundle of wires e' for the primary are suitably located beneath the primary coil, or between the coil and bore of the spool e. I prefer, however, for convenience of making or building up said core and placing it in position, to insert within the bore of the spool e a second spool, H, having a shoulder, h, at one end, and shellacing or otherwise securing the wires forming core e' to the outside surface of spool H, as shown in Fig. 1. The primary coil or its spool may be fastened to back of the box, or the closed end of spool H may be secured to the back of the box A, to keep it and the primary, as well as the block F in a fixed, 60 position, or the primary may be loosely pivoted or connected to said back or to a lug, k, thereon, and have a set or thumb nut, k', for retaining it in position, as shown in Fig. 2. This last-described construction admits of adjusting the inclination of the primary coil and block F to vary the degree of initial contact 70 between the electrodes. 75

I do not limit myself to any size or diameter of spool e for the secondary current, as it may be made large, as shown in Fig. 1, or just large enough to admit of inclining the primary coil within it, as shown in Fig. 2. 80

To prevent the ball or electrode G falling out of the bore of the primary coil when the 85 lid a is removed, a metal spring or flexible strip, g, of card-board or other suitable material, is secured to the front end of the spool for the primary coil and arranged to project into the path of the electrode, as shown in Fig. 2. 90

I do not herein claim the relative or proportionate sizes or diameters of the primary and secondary coils of the inductorium I, as this forms the subject-matter of a separate application. 95

If desired, the position of the primary and secondary coils may be reversed—that is, the secondary is the inner and the primary the outer coil; but the results obtained from this disposition of the coils is not as intense as 100

those obtained from the coils when arranged as first above described.

The electrodes *b* *G*, and preferably plate or block *D*, are in the primary of the inducto-
rium *I*, which includes a battery, 2, and its secondary *C* is part of the line.

What I claim is—

1. In a telephonic transmitter, the combination of an induction-coil having in its bore 10 a loose or rolling electrode, a diaphragm in contact with said electrode, and circuit-connections, substantially as set forth.

2. A telephonic transmitter having a diaphragm, an induction-coil having a hollow or 15 tubular core, a rolling electrode within the bore of said core and in contact with the diaphragm, substantially as set forth.

3. In a telephonic transmitter, a diaphragm, an induction-coil having its primary in an inclined position within the bore of the secondary, a loose or rolling electrode within the bore of the primary and in contact with the diaphragm, substantially as set forth.

4. In a telephonic transmitter, an inducto-
rium having its primary coil in an inclined 25 position within the secondary coil, a carbon block and loose or rolling electrode within the bore of the primary coil, and a diaphragm in contact with the rolling electrode, substantially as set forth.

5. In a telephonic transmitter, the combination of an induction-coil having a tubular core, a block, *F*, in said core, a rolling electrode on said block, and a diaphragm in contact with said electrode, substantially as set 35 forth.

6. A telephonic transmitter having an inductorium, the bore of the primary coil of which forms an inclined table for a loose or rolling electrode, and means for altering the 40 inclination of primary, substantially as set forth.

7. A telephonic transmitter having an inductorium the primary of which is separate from the secondary, a pivoted support for the 45 primary, and adjusting devices for placing and inclining the primary within the bore of the secondary and for varying its inclination, a loose or rolling electrode in the bore of the primary, and a diaphragm in contact with said 50 electrode, as set forth.

In testimony whereof I affix my signature in presence of two witnesses.

JAMES W. BONTA.
